UNITED STATES PATENT OFFICE.

CLYDE S. WRIGHT, OF TOLEDO, OHIO, ASSIGNOR TO THE NATIONAL SUPPLY COMPANY,
OF TOLEDO, OHIO, A CORPORATION OF OHIO.

CASING-HEAD TOP.

1,343,426.

Specification of Letters Patent. Patented June 15, 1920.

Application filed December 6, 1919. Serial No. 342,890.

To all whom it may concern:

Be it known that I, CLYDE S. WRIGHT, a citizen of the United States, residing at Toledo, in the county of Lucas and State of Ohio, have invented new and useful Improvements in Casing-Head Tops, of which the following is a specification.

My invention relates to casing-head tops provided with means for suspending thereon the tubing in which the pump-rods of oil wells reciprocate. It is the common practice to suspend the tubing in the well-casing by means of a collar or coupling connecting two sections of the tubing and resting on a tubing ring on the upper end of the casing-head. Before this particular coupling is applied to the tubing, the latter is lowered through the casing until its lower end reaches the bottom of the well, at which time 15 the tubing is marked at the level of the top of the casing-head. The tubing is then raised to give it proper clearance from the bottom of the well and again marked at the same level. The joint or length of tubing so 20 marked is removed, cut off at the second mark, and the end thereof which was removed from the tubing still in the casing is threaded externally. A coupling is screwed 25 on the newly made threads and a length of tubing carrying the T-head at the top of the tubing is screwed into the upper end of the coupling. The tubing is then lowered until 30 the coupling rests upon the tubing ring. The upper one of said marks made on the 35 tubing serves to indicate the amount of the said clearance.

The defects of this manner of suspension of the tubing are, first, it is almost impossible for ordinary workmen at the well to cut 40 as good a thread with hand tools as pipe-mill manufacturers can with machine tools at the place of manufacture; so that defective joints are often made which are liable to leak or pull out after the tubing has been 45 put back into the well and suspended on the said coupling; and second, there is always the possibility of something falling against the tubing above the casing-head and breaking it off in the threads under the coupling, 50 thereby allowing the tubing to drop to the bottom of the well.

My principal objects are to provide for the tubing an improved suspension means which is without threads; to give the tubing 55 such lateral support that it cannot be broken

off at such a point as will let it fall; and to utilize the suspension device as a part of the means for elevating and holding the tubing preparatory to removing the length thereof above the said coupling thereby requiring 60 but one elevator. Other objects appear hereinafter.

Referring to the accompanying drawings, Figure 1 is a central vertical section through a casing-head and my invention applied thereto, the pump-tubing being shown in such elevation and the casing being in vertical section and broken off. Fig. 2 is a view similar to Fig. 1 showing a second stage in the operation of this invention, parts being 70 omitted. Fig. 3 is a perspective view of the upper tubing-ring; Fig. 4, a perspective view of the lower tubing-ring; Fig. 5, a top plan view of the slips by which the tubing is gripped during suspension; and Fig. 6, a 75 perspective of the slips.

On the drawings, 1 designates the well-casing supporting at its upper end the casing-head 2 of usual construction. The casing-head has at its upper end the usual internal annular flange 3, on which the external flange 4 on the periphery of the lower tubing-ring 5 rests. The tubing-ring 5 has at its lower end the annular inturned flange or shoulder 6 on which the lower packing-ring 7 rests. On this ring the annular packing 8 is supported. This packing in turn supports the upper packing-ring 9.

The length 10 of the pump-tubing extends through the said packing and packing-rings, 90 and has at its lower end the coupling 11 which connects it to the tubing section 12 below. The upper end of the tubing-section 10 bears the T-head 13 of the pump, 14 being the outlet for the oil pumped up the 95 tubing and 15 the pump-rod extending through the top of the head. The opening within the flange or shoulder 6 is large enough to allow the coupling 11 and other couplings on the tubing to pass.

On the top of the ring 9 is the upper tubing-ring 16 which extends up above the ring 5. Its inner wall tapers downwardly from its upper end as shown at 17 to receive the set or ring of slips 18 surrounding the tubing and tapered on their outer sides so that, when assembled in a ring about the tubing, they will fit in the tapered opening 17. The inner faces of the slips have upwardly-inclined teeth for gripping the tubing and pre- 110

venting it from slipping through the same. The upper end of the central opening of the lower ring 5 is downwardly tapered at 19 to correspond with the opening 17 in the 5 ring 16, so that the opening 19 will receive the set of slips 18 and grip the tubing in the ring 5.

I have shown three slips 18 for a set, but the number may be more or less than three. 10 I provided the hinge-plates 20, one of which overlaps all but one of the joints, or pairs of adjacent edges of the slips. Each end of each plate 20 has a hole 21 elongated at right angles to the plane of the joint it 15 covers, and a pivot screw 22 passes through each hole and into the top of the slip below, the heads of the screws overlapping the plates about the holes. A handle 23 is attached to each of the slips adjacent to the 20 joint which is not covered by a plate 20. Plates 20 may be placed on the bottom of the slips.

The upper end of the ring 16 is provided at opposite sides with the downwardly- 25 hooked ears 24 to which hoisting links 25 may be applied for handling the tubing.

Fig. 1 shows the parts as they are when the tubing is in normal position for pumping. To set the tubing with proper clearance at the bottom thereof, the operator has merely to lower the tubing until it reaches the bottom of the well, then raise it to give the said clearance and set the ring of slips 30 into the tapered opening 17 in the upper tubing-ring 16. The tubing is then cut off at the proper distance above the casing-head, and a thread is cut on the end of the tubing and in the said position. The T-head 13 is screwed on the threads. The tubing is 35 not by my invention supported on threads made in the field, but wholly by the slips 18 and there is no danger of the tubing being broken off so low by something falling against it as to allow the tubing to drop 40 down the casing.

In the operation of pulling the tubing out of the well-casing 1, a hoisting device such as a regular tubing or casing hook, would be passed through the upper ends of the two 45 long links 25 hooked under the ears 24. As soon as the first tubing-coupling 11 comes in contact with the lower ring 7, it lifts both the rings 7 and 9 and the packing 8 clear of the lower tubing-ring 5. When the coupling 50 11 is well above the ring 5, an elevator of usual construction is laid upon the tubing-ring 5 and placed around the tubing in the usual way. The tubing is then lowered until the coupling 11 rests on the elevator in 55 the usual manner. The length 10 of the tubing is removed from the coupling 11. The hoisting device is then disconnected from the links 25 and connected to the elevator and the tubing raised until another coupling 60 on the tubing comes above the tubing-ring 5,

when the set of slips 18, which have been removed from the tubing-ring 16, are inserted into the opening 19 and the tubing allowed to settle back on them as shown in Fig. 2. The section of tubing above the said coupling is then removed and the elevator, which has been taken from this section is put under the coupling at its lower end. The hoisting device is connected to the elevator and the tubing again raised, the ring of slips 70 18 being removed from their seats and replaced therein below the next coupling which comes above the ring 5. These steps are repeated until the required number of lengths of tubing has been removed. It is thus seen 80 that I employ only a single elevator whereas the usual practice requires two, one to do the elevating and the other to support the tubing sections just above the tubing-ring.

It is to be noted that, by connecting the 85 slips together pivotally except at one joint, they can be handled by one man and kept in alinement with each other. The handles being on the slips next to the joint without hinge-plates make it easy to open and close 90 the ring of slips.

I claim:

1. The combination of a casing-head, upper and lower tubing-rings adapted to surround a string of tubing and each having 95 the upper end of its opening correspondingly tapered downwardly, slips adapted to be seated in the tapered portion of either opening and grip a section of said string and suspend the string on the corresponding tubing-ring and means on the upper ring for attaching a hoisting device.

2. The combination of a casing-head, upper and lower tubing-rings adapted to surround a string of tubing and each having 105 the upper end of its opening correspondingly tapered downwardly, means for securing the lower tubing ring to the casing-head, slips adapted to be seated in the tapered portion of either opening and grip a section of 110 said string and suspend the string on the corresponding tubing-ring, and means on the upper ring for attaching a hoisting device.

3. The combination of a string of tubing, 115 a casing-head surrounding a section of the string, a tubing-ring surrounding the said section and supported by the casing-head, packing surrounding the said section and supported by the said tubing-ring, a tubing-ring surrounding the tubing above the packing and resting thereon, and slips adapted to be seated in an enlargement of the upper end of the opening in each tubing-ring, whereby the string may be supported from either 120 tubing-ring at will.

4. The combination of a string of tubing, a casing-head, a tubing-ring thereon having the upper end of its opening tapered downwardly, slips adapted to be seated in the said 130

opening and to grip a section of said string and suspend the string on the tubing-ring, and means for pivotally connecting adjacent slips together.

5. The combination of a string of tubing, a casing-head, a tubing-ring thereon having the upper end of its opening tapered downwardly, slips adapted to be seated in the said opening and to grip a section of said string and suspend the string on the tubing-ring, and means for pivotally connecting adjacent slips together, one pair of adjacent slips being without a pivotal connection.

6. The combination of a string of tubing, a casing-head, a tubing-ring thereon having the upper end of its opening tapered downwardly, slips adapted to be seated in the said opening and to grip a section of said string and suspend the string on the tubing-ring, means for pivotally connecting adjacent slips together, one pair of adjacent slips being without a pivotal connection, and a handle on each of the last named slips.

7. A series of slips adapted to form a

ring, plates bridging each joint but one between adjacent slips, and pivots extending through the plates into the slips in contact therewith. 25

8. A series of slips adapted to form a ring, plates bridging each joint but one between adjacent slips, and pivots extending through the plates into the slips in contact therewith, the pivot openings in the plates being elongated in directions at an angle with the meeting plane of the adjacent slips. 30 35

9. The combination of a tubular holder having its bore tapering from one end, a plurality of slips adapted to form a ring having its outer surface tapered to correspond to the taper of the holder and its 40 interior surface provided with gripping teeth to bite against a pipe engaged by the said slips when seated in said holder, and means hinging together some of the adjacent slips. 45

Signed at Toledo, Ohio, this 29th day of November 1919.

CLYDE S. WRIGHT.
